The ornamental design for a food package for frozen or shelf-stable foods, as shown.

DESCRIPTION

FIG. 1 is a perspective view of a food package for frozen or shelf-stable foods.

FIG. 2 is a top plan view of the food package for frozen or shelf-stable foods of FIG. 1.

FIG. 3 is a bottom plan view of the food package for frozen or shelf-stable foods of FIG. 1.

FIG. 4 is a left elevation view of the food package for frozen or shelf-stable foods of FIG. 1.

FIG. 5 is a right elevation view of the food package for frozen or shelf-stable foods of FIG. 1.

FIG. 6 is a front elevation view of the food package for frozen or shelf-stable foods of FIG. 1; and,

FIG. 7 is a back elevation view of the food package for frozen or shelf-stable foods of FIG. 1.

In the drawings, the broken lines depict unclaimed subject matter only and form no part of the claimed design.
